(57) **CLAIM**

The ornamental design for a bottle, as shown and described.

DESCRIPTION

FIG. 1 shows a perspective view of a design for a bottle.

FIG. 2 shows a side view of the design.

FIG. 3 shows a top view of the design; and,

FIG. 4 shows a bottom view of the design.

The broken lines in the drawings illustrate the portions of the bottle that form no part of the claim.
